STOP MOTION FOR LOOMS

Walter J. Budzyna, East Douglas, Mass., and
Maurice R. Flamand, Central Falls, R. I., as-
signors to Draper Corporation, Hopedale, Mass.,
a corporation of Maine

Application August 6, 1949, Serial No. 109,036

16 Claims. (Cl. 139—353)

1

This invention pertains to improvements in loom stop motions, and more particularly, to stop motions especially adapted for use on shuttleless looms or those of a type which draw filling from an outside source of supply.

It is a general object of the invention to provide in shuttleless looms or looms of a type adapted to draw filling from a source of supply not carried by a shuttle, a simple and effective stop motion adapted to stop the loom either upon failure of the mechanism to lay the filling in a prescribed manner or upon failure of a warp thread.

It is a further object of the invention to provide a combined filling and warp stop mechanism, the knock-off actuating mechanism for which is greatly simplified and which functions through a common linkage to stop the loom upon failure of either the filling or warp threads.

It is a further object of the invention to provide simple and effective means for stopping a loom of the type described whenever a filling thread is broken or fails to be inserted in the shed in a prescribed manner, and which shall function in a very short period of time as is necessary with shuttleless looms or other looms of that type which function to insert filling from an external source of supply.

It is a further object of the invention to provide simplified means adapted to function upon breakage or failure of either the filling or warp threads in looms of the type described and which shall set in motion or vary the position of certain elements which function through very accurately timed devices to effect the knock-off function in a precise, but adjustably timed relationship to the movements of the lay and to the movements of the filling carrying instrumentalities.

Further objects will become apparent from the following more detailed disclosure.

In shuttleless looms and particularly in looms employing flexible tapes or other elements moving inwardly of the shed formed within the warp threads and adapted to deposit or lay filling from a source of supply maintained at the ends of the loom and beyond the edges of the fabric being woven, the problem of providing a filling stop motion is much more difficult than in the conventional fly shuttle loom. It is not practical to employ filling feeling forks or other devices at the ends of the shed or adjacent thereto for sensing the presence or absence of the filling as it extends between a shuttle and the warp threads at the shed ends as is the usual practice. Stop mechanisms for shuttleless looms must be adapted to function at a point within the shed

2

and further, must function after the filling has been almost completely laid in the shed and after at least a partial withdrawal of the filling carrying instrumentalities therefrom. Thus the problem is one much more difficult than in the conventional loom and must employ devices which function very rapidly and yet which must accurately and faithfully sense the presence of filling without seriously affecting its position or the manner in which it is held within the shed since, if that were to happen, the finished fabric would show marks resulting from pressure of the filling feeling means, that obviously being something which could not be tolerated.

15 The stopping of the loom must be so controlled that the parts always come to rest at a particular point in the cycle at which the filling carriers will have been withdrawn from the shed and the harnesses leveled. Therefore the feeler mechanism must act within a very short period of time and set in motion or energize certain other parts forming a portion of the complete stopping mechanism without fail so that the loom may be knocked off with certainty whenever the condition of the filling or that of the warp threads is such that attention is required before weaving should continue.

20 In carrying the invention into practice, filling and warp stop motions are employed which function largely through mechanical means for knocking off the loom as by disengaging the clutch and applying a brake. The mechanisms, however, function electrically to an extent. The failure of a warp thread or absence of filling in the shed is effective to vary a circuit in a manner to energize certain solenoids or similar electrical means for positioning certain mechanical elements in the path of a periodically movable actuator controlled by cams which accurately time the point at which the knock off shall occur. The warp stop mechanism parts of which are of conventional type and the electrical and other details of which are well known is connected within a circuit hereinafter to be described in greater detail and which function through a solenoid individual thereto to position a detent in the path of the said moving actuator. The filling stop motion which is preferably carried by the moving lay and which involves one or more filling feeling mechanisms employing relatively thin members adapted to be projected between the warp threads and to descend into contact with the filling if it is properly placed, is interconnected to other periodically moving means which, 25 upon failure of the feeling means to contact a

properly laid filling thread, functions to actuate certain switch means or other electrical devices within the circuit which then control a similar solenoid or other electrical relay device such as may position a similar detent within the pathway of the moving actuator and will then initiate the stopping movement which, in properly timed relationship to movement of the loom parts, knocks off the loom as will hereinafter be described.

The invention will be described in following paragraphs by reference to one preferred embodiment thereof and certain modifications, the disclosure and illustrative drawings being given by way of example of a preferred form which the invention may take.

In the figures of drawing:

Fig. 1 is a perspective view of the right hand end of a shuttleless loom to which the invention has been applied, this view showing certain details of the general arrangement of the parts and the general manner in which the stopping means has been applied thereto.

Fig. 2 is an enlarged perspective view of some of the stop motion mechanism which forms a part 25 of the more inclusive showing of Fig. 1.

Fig. 3 is a front elevation of one end of the lay and showing part of the center fork movement applied thereto.

Fig. 4 is a section taken through a part of the loom and showing the mechanism of Fig. 3 as seen from a different viewpoint.

Fig. 5 is a detail view showing to an enlarged scale the center fork switch contacting means illustrated in Figs. 3 and 4.

Fig. 6 is a front elevation of the mechanism shown in Fig. 5.

Fig. 7 is a detail view of a cam from which the center fork movement is derived.

Fig. 8 is an end view of the cam shown in Fig. 7.

Fig. 9 is a detail view of the center fork cam.

Fig. 10 is an end view of the cam of Fig. 9 and showing the angular disposal of the operative surfaces thereof which engage an arm attached to and used for swinging the center fork tines to 45 their different positions.

Fig. 11 is a plan view of the stop motion actuator lever cams showing angular disposal and other details thereof.

Fig. 12 is a section taken through the vertical 50 center line of Fig. 11 and further illustrating details of the cams shown therein.

Fig. 13 is a wiring diagram showing an electrical circuit which may be employed.

Now referring to Fig. 1, the general arrangement of parts which enter into the combination will be briefly described. One loom to which the stop motion may be applied is herein illustrated, although it is to be understood that the invention applies to conventional looms and to all types of shuttleless looms such as needle looms, looms employing flexible tapes to introduce the filling, or to looms employing other filling carriers which may be projected through the shed, but which receive the filling to be inserted from an external source of supply and therefore, in most instances, lay filling in lengths which are not continuous.

The loom may have loomsides 20 and other structural parts within which are adapted to function the various loom mechanisms including a let-off (not shown) but by which warp threads generally designated by numeral 21 are drawn through heddle mechanisms 22 operated in any conventional manner, and a fabric take-up means

(not shown). The filling maintained as a stationary, outside source of supply and herein located within a container 23, one of which is to be found at each end of the loom, is drawn therefrom through a conduit 24 and is so controlled by filling motions generally indicated by numeral 25 and which need not be described in detail here, is carried into and drawn across the shed to be laid therein as independent or individual picks of filling in a manner understood by those conversant with this art. The particular means for introducing the filling comprises at either side of the loom, a flexible tape 26 adapted to be projected into and withdrawn from the shed by an oscillating tape wheel 27 enclosed within a casting 28 and actuated by means including a system of gearing (not shown).

At one end of the machine a driving motor 29 is mounted upon a suitable bracket and is connected through a clutch and gearing to drive a main cam shaft 30 from which other parts are driven or moved in timed relationship and in proper synchronism with the various functional parts, thereby to carry out the weaving steps in a prescribed manner. Reference is hereby made to co-pending application Serial No. 71,622, filed January 19, 1949, now U. S. Patent No. 2,604,123, and wherein a loom similar to that herein described is more fully disclosed.

The stopping of the loom is effected upon breakage of a warp thread or upon failure of the filling inserting mechanism properly to insert a pick of filling within the shed. As shown in both Figs. 1 and 2, the actual knocking off or stopping of the loom is effected through a moving actuator lever 31 pivoted at 32 on a bracket or other support member 33 and normally urged by means of a spring 34 in such direction that a follower 35 at the free end thereof is caused to bear with a definite pressure against the inner surface of a cam disc 36 or upon certain cams 37 or 38 thereon, the function of these cams being explained in greater detail hereinafter. The cam disc 36 also carries a third cam numbered 39 projecting from the otherwise circular periphery thereof, this cam bearing a definite spaced relationship to the cam 37. By means of a locking screw 40, the position of the disc 36 and its attached parts may be angularly varied as a whole. The cam 38 is fixed to the disc 36 by means of a threaded projecting stem 41 passing through a slot 42 in the disc and adapted to be locked in position by the nut 43. Thus cams 37 and 39 may be angularly adjusted throughout a reasonable extent and cam 38 may be similarly moved angularly independently thereof.

These parts are mounted upon the continuously rotating cam shaft 30 and thus make one complete revolution every time a pick of filling is inserted. It is to be understood that the parts just described and those which, as hereinafter described, function therewith may be attached to and may be operated by any other moving shaft or element within the machine which may be conveniently employed. The principles of operation will remain the same.

The lever 31 which constitutes a constantly moving actuator carries a contact member 44 in the form of an adjustably positionable bolt head and is adapted to be moved by the cams 37 and 38. Upon failure of a warp thread, or of a filling thread to be inserted properly, the member 44 contacts certain detents 45 or 46 as the latter are moved to or are permitted to be moved to 75 a position in the pathway of the contact member

44. Each of the detents is pivoted on a supporting arm 47, detent 45 being pivoted on the pin or screw 48 and detent 46 being pivoted similarly at 49. This arm 47 is a part of a clutch control lever later to be described. Each of these detents has hooked or otherwise connected thereto a link generally indicated by numeral 50 and which comprises two hooked wires joined at the center by an adjustable clamp or otherwise so formed that, preferably, the length thereof may be adjusted, the other end of said link being hooked to or otherwise attached within the end of a two-armed lever 51 pivoted on a cross bolt or other pivot member 52 adjacent the top and offset from the center of a casing 53 within which are housed the coils and other parts including an armature or core for the solenoid. The lever 51 extends to the other side of its pivot and has connected thereto a spring shown in Figs. 2 and 13, by means of which the lever and thus the detent are normally retained in an uppermost position, or at least, in an inactive position with respect to the contact member 44 so that unless one of the stop mechanisms initiates a stopping action, the movement of the lever 31 by means of the cams above mentioned is an idle or ineffective one.

Corresponding parts in the other solenoid casting 54 are not numbered and need not be described since they are identical with, or at least similar to those just described. The two detents 45 and 46 are thus adapted to be moved downwardly against the tension of the springs 55 whenever stopping of the loom is initiated, the downward movement thereof being limited by a ledge or other stop element 47 which preferably forms a part of the supporting arm 47.

The arm 47, as hereinbefore stated, is actually a part of the clutch operating fork which is integrally or otherwise formed as a part of an arm 56 in turn pivoted at 57 and which, in effect, is an extension of the curved shifter lever 58, it being understood that both the arm 56 and the lever 58 pivot upon the stud or pivot point 57, and that the lever 58, as illustrated in Fig. 1, is connected at its inner end to a link 59, the other end of which is connected to one arm of a bell crank lever 60. The bell crank lever 60 may rock on a stud 61 fixed in the loomside or in another rigid portion of the machine and, in turn, is interconnected to the front shipper lever shaft 62 through a link 63 which connects at its lower end to the more or less horizontally disposed arm of the bell crank lever 60, and at its upper end, to an arm 64 rigidly connected to the shaft 62. Shaft 62 also has fixed thereto the right hand shipper lever 65 and at its opposite end, a similar lever (not shown).

In starting the machine, the lever 65, or that at the opposite end of the machine, is merely pulled outwardly thereby moving the linkage just described so that the inner forked end of the arm 56 is moved toward the end of the machine or outwardly along shaft 30 to shift a clutch actuating collar which controls the position of certain clutch fingers thereby to engage the clutch for driving the machine. The opposite movement of the parts permits the fingers to move to a different position in which they do not effect engagement of the clutch interengaging and driving elements. The shipper levers, the clutch itself and the clutch engaging and disengaging means form a part of practically all looms and their construction and the mode of operation are well known to those skilled in this

art. Further description thereof is not necessary here.

The swinging movement of the actuator 31 shifts the parts just above described in the event 5 that either detent 45 or 46 has been displaced to a position to be engaged by the contactor element 44. Since these detents are actually a functional part of the clutch fork including arm 56 and the fork extension 47, either of cams 37 or 38 pushing against follower 35 and through the intermediary of the contactor 44, will move the fork inwardly along shaft 30 toward the center of the machine a sufficient distance to effect knocking off of the machine by disengaging the 10 clutch, the interconnecting linkage shown in Fig. 1 simultaneously moving the shipper levers to that position which they occupy when the machine is stopped. A brake may or may not be employed, but is preferable that one be used 15 so that the amount of movement or coasting of the loom after the clutch is disengaged may be more precisely controlled and kept near a minimum. Normally a loom of this type may rotate from about one-half revolution to something approaching a revolution and one-half depending 20 upon the condition of certain elements and the speed at which the loom is being operated. It is desirable to keep the coasting movement down to a minimum and also positively to govern the amount of travel of the loom after power has 25 been discontinued since it is thereby easier to adjust the cams 37 and 38 permanently in position and to make certain that the loom will stop with the harnesses in very close to a level or 30 centrally disposed position.

If a brake is employed it may take any one of the forms heretofore found quite satisfactory for conventional looms since it is merely desired to have some retarding influence applied as soon as 35 the power or driving means has been disengaged.

Now having described the novel mechanism by which the loom is knocked off or stopped when stopping has been initiated at either a warp stop motion or a filling stop motion, the latter sometimes being referred to as a center fork if it functions within the lateral confines or intermediate the terminal warp threads as they are separated to form a shed within which the filling may be inserted, the individual stop initiating 40 motions themselves will be disclosed. In Fig. 1 a warp stop motion generally indicated by numeral 66 is supported at the upper part of the rear portion of the loom and, as herein illustrated, is preferably an electrical type warp stop motion. A complete description thereof is not necessary 45 here since the essential features of that part of the stop motion itself are described and shown in U. S. Patent 2,378,895 and involve a series of insulated contact members between which an electrical connection may be established upon release of any one of a plurality of so-called drop wires 67, each of which is supported by one of the warp threads. When a thread breaks or for any other reason is not present under proper tension, its drop wire moves to a position to establish 50 an electrical contact or connection between the said insulated bars and will thereby complete a circuit through to the solenoid enclosed within the box 53 and which governs or controls the position of detent 45 in such a manner as to move it downwardly against the tension of its spring 55 until it is interposed in the pathway of the contact member 44, above described. The 55 stopping of the loom then may be completed as 60 the cam 38 which is employed for the purpose of 65 the cam 38 which is employed for the purpose of 70 the cam 38 which is employed for the purpose of 75 the cam 38 which is employed for the purpose of

stopping the mechanism whenever a warp stop is indicated, moves the actuator arm 31 to carry through its intended purpose.

It is obvious that a warp thread may break at any time or at any point in the cycle of movement of the loom parts. In order to prevent completion of a warp stop except by the cam 38, that is, to prevent completion of a warp stop through the cam 37 which, of course, would be the first cam to contact follower 35 if the warp thread happened to fail just prior to the approach of that cam and after cam 38 had passed the follower, the cam 39 adjacent cam 37 prevents the detent 45 from being drawn down by the solenoid until cam 37 has passed by follower 35. Cam 39 holds detent 45 in elevated position whenever that cam underlies the laterally projecting wire or extension 68, Figs. 1 and 2.

Now referring to Figs. 3, 4, 5 and 6, parts of the loom which affect stopping thereof upon failure of the filling to be inserted properly will be described. The lay movement for a loom of this type comprises a lay beam 69 carried by swords 70 which are pivoted on a rock shaft 71 adjacent the lower part of the loom and, although it forms no particular part of the present invention, this lay beam and these swords may be swung to and fro in properly timed relationship by cams 72 and 73 on main cam shaft 30, these cams functioning upon followers at the ends of the fork-like arms 74 and 75 which in turn are a part of the structure to which the swords 70 are adjustably attached and by means of which the rocking movement derived from the cams is imparted through to the lay structure itself. That lay structure preferably includes, in addition to the beam 69, a hand rail and a reed 76 forwardly of which is disposed a race plate 77 upon which are adapted to be supported in their movement into and from the shed formed by the harnessed warp threads, a tape and tape heads or filling carriers herein generally indicated by the numeral 78, it being understood that all of these parts and the particular mode of operation incidental thereto are thoroughly described in the application above mentioned. It is also to be understood that the invention is not at all limited to being employed in a loom wherein the lay and parts incidental thereto and wherein the filling itself is manipulated by elements such as herein shown and as described in that application above mentioned.

The cams 72 and 73 are preferably of a form to impart to the lay structure an extended period of dwell consuming about one-half the complete cycle incidental to inserting a pick of filling, the remainder of the cams being so formed as to move the lay in a beat-up movement during the remainder of the cycle and after the filling carriers have been moved from the shed and beyond the lay beam 69 which is, of course, long enough to accommodate the maximum width of fabric to be woven and to provide a reasonable amount of additional supporting surface at either side thereof to which the swords and attendant parts may be attached.

The stop motion devices themselves comprise two center fork assemblies only one of which is illustrated since both are substantially identical. Each of these center forks comprises a bracket or holder 79 bolted or otherwise attached at the front side of the beam 69 and carrying on a pivot 80 a plurality of tines or feeler fingers 81, it being customary to employ from three to five such fingers, although it is

to be understood that the number thereof may vary. These fingers attached to pivot 80 are caused to move upwardly through the warp threads as illustrated in Fig. 4 at a particular time during the cycle, but are at other times maintained in a downward position where they lie within a slot or indentation in the race plate 77. On their downward movement, they normally encounter a filling thread which is held between the warp threads and maintained sufficiently taut to support the tines 81 against the downward pull of a tension spring 82 attached to a short arm fixed to pivot 80. The spring is connected at its other end to a hook 82 extending outwardly from the lower part of the bracket or from any other convenient fixed element. In the cycle of operation of these center forks, they are moved upwardly prior to the insertion of the filling, then are permitted to be drawn downwardly by the springs 82 whereupon they either encounter the filling if it is present and properly laid in the shed, or are permitted to drop clear down to the recess in the race plate in the event the filling is not present and in a prescribed position.

For the purpose of raising the tines, a curved arm 83 forming a part of pivot 80 is engaged by a cam 84 better shown in the detail views, Figs. 9 and 10, which will presently be described. A second spring 85 is coiled about the arm 83 where it extends outwardly from the fork pivot and assists in starting the fork downwardly through the warps quickly; it also tends to prevent overthrow as the tines are moved upwardly at a relatively rapid rate by the highest lobe on cam 84.

It is to be understood that the actual period of time available for feeding the filling is exceedingly small and that the parts move at a very rapid rate.

These cams 84, one for each center fork, are detachably fixed to sleeves 86 which are in turn adjustably fixed along the length of a rod 87 reciprocable lengthwise of the lay beam 69. This rod is carried in bearings such as the bearings 88 at the lower parts of the brackets 79 and extends toward one end of the beam 69 thereby to terminate in a connection by which it is attached for operation by an upwardly directed arm 89 of a two-armed lever pivoted at 90 and having a horizontally disposed arm 91 the outer flattened end of which rests upon a tappet 92 at the upper end of a vertically reciprocable bar 93. This bar is guided adjacent its upper end in a bearing 94 connected to the sword 70 and at its lower end is attached to a forked guide member 95 which restrains the parts to axial movement since the forked ends thereof engage at either side or within a groove in a cam hub 96 formed as an integral part of the cam 97, these latter parts being shown in detail in Figs. 7 and 8. The forked guide member also supports a follower 98 which bears upon the cam 97 and which is preferably a roller mounted on a bearing extending outwardly from the said forked guide 95. A spring 99 compressed between the lower end of bearing 94 and an adjustable collar 100 normally urges the vertically reciprocable parts just described in a downward direction or in such direction as to maintain engagement between the follower 98 and the cam 97. In operation of the loom the swinging movement of the sword is accompanied by a corresponding swinging movement of the reciprocable bar or filling fork actuator since both are pivoted or swingable about the rock shaft 71.

The cam 97 and its hub 96 are freely rotatable upon the rock shaft and are driven by a chain 101 which passes about a sprocket 102 the hub of which is fixed to cam shaft 30 and about a similar sprocket designated by numeral 103 and fixed to the hub of the cam 97.

Now referring to Figs. 9 and 10, the cam 84 which is adapted to control the movement of the center fork tines 81 and also to prevent movement of rod 87 to its fullest extent in one direction whenever filling is not properly present in the shed, comprises a more or less level or inactive surface 104, a notch 105 and an inclined, elevated portion 106. These cam surfaces function to control the center fork feeler tines and to set the parts controlled by the shaft 87 to initiate stopping as described generally in United States Patents 1,865,930 and 2,378,240. The top-most part 106 of the cam engages beneath the arm 83 angularly disposed with respect to the pivot 80 for the center fork tines, and thereby elevates the tines to the position of Figs. 3 and 4 whenever the cam 97 lifts follower 98 to move the bar 93 vertically upwardly and, through the lever arms 91 and 89, push the rod 87 to the left against the tension of a spring 107 engaged between the bearing 88 and an adjustable collar 107', all as shown in Fig. 3. It is to be understood that two center fork assemblies are preferably provided and that the rod 87 extends further to the left thereby to control the second center fork motion in precisely the same manner that it controls the center fork herein shown. It is not necessary to show both where the additional showing would merely involve duplication. The cam surfaces 104, 105 and 106 are inclined as shown to provide a better bearing for the arm 83.

The extent of the raised portion of cam 97 is shown in Fig. 8 and it is throughout that angular part of the cam's rotation that the center fork is held in its elevated position. Upon further rotation of the cam 97, the rod 87 is permitted to return to the right, Fig. 3, under the influence of spring 107, and the tines 81 are then permitted to fall under the influence of springs 82 and 85, that particular part of the mechanism being more fully illustrated in the U. S. Patent 2,378,240, the tines moving downwardly as the arm 83 follows the contour of the cam surface 106 until they rest upon the filling providing that filling is present in the shed as it should be. In that position, the arm 83 is arrested before it moves down into the notch 105 so that the return movement of the cam 84 with rod 87 fails to effect engagement between the point 108 and the arm 83, so long as filling is present beneath the tines 81. The tines do fall to a lower position and the arm 83 may be brought to rest on cam surface 104, but that occurs during the beat-up and after the point 108 of the cam 84 has passed the arm 83 in the movement of the parts toward the extreme right hand position.

In the event filling is not present as the tines 81 move downwardly, they are not arrested as above described and fall into a depression or groove in which they are disposed beneath the normal surface of the race plate 77, and simultaneously, the arm 83 follows the surface of cam 106 down to an elevation beneath the point 108 of the cam at the left hand side of the notch 105. That then arrests the movement of the rod 87 in its return to the right for a sufficient period of time for the stopping cycle incidental to filling failure to be set in motion.

Now referring to Figs. 3, 4, 5 and 6, the ver-

tically disposed arm 89 which swings to and fro with the rod 87 and cam 84 has projecting therefrom in a forward direction, a contact finger 109. This finger 109 moves between extreme 5 positions as indicated by dot-and-dash lines, Fig. 5, but when upon filling failure, the cam 84 is arrested by presence of the arm 83 in the notch 105, the parts are temporarily positioned in the full line position of Fig. 5, so that upon 10 the forward or beat-up movement of the lay, this finger 109 engages a plunger 110 of a microswitch or other switch generally indicated by numeral 111 and which forms a part of the stop motion circuit hereinafter to be described in 15 greater detail by reference to the diagrammatic view, Fig. 13. When filling is laid in the shed in a normal manner, the arm 89 and contact finger 109 return to the full right hand position, and, in that position, there is no effect 20 upon the microswitch so that the only possibility of engagement between the finger and the plunger or other part of the switch adapted to change its effect upon the flow of current in the circuit takes place when the cam 84 and rod 87 25 have been arrested in midposition, as above described.

The movement of the arm 89 is limited by stops 112 and 113 which project forwardly at either side of the arm and form a portion of a 30 casting connected to the lay structure adjacent that point and which also extends downwardly to support the pivot 90 for the arms 89 and 91.

Now referring to Fig. 13, certain parts heretofore described have been illustrated in a more or 35 less diagrammatic fashion and are shown within the circuit in which they function. Current from any convenient source is introduced to a primary 114 of a transformer, the secondary 115 of which is grounded at one side at 116 and connects 40 through to the stop motion circuit at its other side, such connection being effected through a switch 117. This switch 117, not shown in any of the other views, is preferably positioned beneath the left hand knock-off lever so that an extension thereof may operate the switch to throw the current off or to open the circuit whenever the loom 45 is stopped. Then upon restarting the loom the said extension on the knock-off lever, or any other satisfactory control means for the switch, will reset it thereby to close the circuit and to introduce current to the various parts thereof, it being understood that the circuit which is grounded is not completed until one or the other of the 50 stop mechanisms functions.

At the warp stop motion side of the circuit one of the grounded conductors in which is mounted an insulated conductor is shown, a drop wire 67 being in that position which it occupies when the warp thread controlled thereby is present and 55 under proper tension. The insulated, non-grounded conductor is connected to the coils of the solenoid 53 for the warp stop detent 45. The other end of the said solenoid coils being connected to the secondary of the transformer through the switch 117, it being understood that switch 117 is normally closed when the loom is 60 running.

The other solenoid 54 which controls the position of its detent in accordance with filling conditions present at the lay as indicated by the center forks is also energized from the secondary 115 through switch 117 and the conductor illustrated. The other end of the coils of that solenoid is connected to a ground through switch 111, that is, 65 the microswitch, which is tripped only when one

of the center forks fails to sense the presence of filling at the lay in proper position preparatory to being beaten into the warp. It becomes evident that upon the downward movement of a drop wire 67 or upon tripping and closing the microswitch 111, that the appropriate solenoid at casings 53 or 54 will be energized thereby moving the corresponding detent 45 or 46 downwardly, the loom then being knocked off by engagement of contact member 44 with that detent moved to its lowermost position. It is obvious that other circuits may be employed and that herein illustrated is merely given by way of example.

Now referring to Figs. 11 and 12, a modified form of cam has been illustrated, this cam being possible of substitution for the cam 36, Fig. 2. The cam lobes 37' and 38' correspond to the similar lobes 37 and 38 and are preferably attached and the lobe 38' made adjustable in the same manner as has heretofore been described with respect to the cam 36, the simple cam disc 36 here being replaced by a cup-shaped member 118 having a hub 119 attachable and adjustable by means of a set screw to the shaft 30, or other appropriate rotating element upon which the cam may be carried. In order to shorten the extending wire 68 and to render the action of cam 39' which corresponds to cam 39, Fig. 2, more precise and direct, the said cam 39' is formed at the inner end of a cylindrical extension 120 which may form an integral or attached part of the disc 118. This cylindrical portion 120 also serves to enclose to some extent the cams 37', 38' and the follower 35 which functions therewith. In Fig. 11 the various angular extents of cam surfaces which have been found to function quite satisfactorily in actual practice have been designated as and applied to the several cams. It is to be understood that these figures are illustrative of one embodiment of the invention which has been employed in actual practice, and are not at all limiting since under different designs for the mechanism the timing of certain of the parts may be varied to an extent and therefore the actual figures hereby given by way of example would necessarily vary accordingly.

The form of the invention shown and described to this point involves electrical contact being made at some point whenever a warp thread breaks or filling fails to be inserted properly, that electrical contact initiating the movement of certain mechanism which eventually causes the loom to stop. It is to be understood that the invention may be modified in such manner as to convey the initial impulse or movement of parts which is incidental to failure of a warp thread or filling to be inserted properly by means which is wholly mechanical in nature. That means, not herein described, would take the place of the circuit which includes contact means, switches, and solenoids energized upon completion of one of the circuits, and such mechanical devices would then move the detents 45 or 46, as the case might be, into position to be engaged by the contact element 44 on the continuously moving actuator arm 31. Whenever that occurred, the loom would be stopped in the same manner as hereinbefore described.

Operation

During normal operation of the loom the warp threads are maintained under sufficient tension to hold each of the drop wires 67 in uppermost position in which event no contact is made at the warp stop motion side of the circuit so that

the solenoid enclosed within casing 53 is not energized and the detent 45 is therefore held by means of spring 55 in an upper, or, at least, in an inactive position. Detent 46 is likewise maintained in a position where it cannot be engaged by the contact member 44 which, of course, is periodically moved under the action of cams 37 and 38. Whenever a warp thread fails or for any other reason, one of the drop wires 67 falls, contact is made within that part of the circuit which is utilized for energizing the solenoid at 53 so that the warp stop side of the mechanism immediately tends to function for drawing the lever 51 downwardly to position the detent in the pathway of the moving actuator contact member 44. In the event the cam 37 has just passed by the follower 35, the action of the solenoid is immediately completed and cam 38, when it does engage follower 35, pushes the clutch actuating fork inwardly as above described thereby to disengage the clutch parts and, through the levers 35, 58, 60 and interconnecting linkage, Fig. 1, the completion of the loom knock-off is completed so that the brake, if a brake is employed, will be set thereby to stop the loom more quickly. At that same time or during the movement just above described, the switch 117, Fig. 13, is thrown to open position to discontinue flow of current in the circuit throughout the entire stop motion circuit.

In the event the initiation of the stopping movement due to breaking of a warp thread occurs before the cam 37 had passed by follower 35, the cam 39 functions to elevate or to maintain in elevated position the detent 45 through its engagement beneath the extending wire arm 68. That assures that the warp stop will not be completed through the cam 37 which is actually only for the purpose of effecting stopping indicated at the center fork or through the filling stopping devices.

In the event filling fails to be inserted properly, such failure being due to breaking thereof, displacement of the filling along the lay for various reasons, or for any other reason of which there may be several, the tines 81 move downwardly after the inserting movement of the filling carriers and just after they have been withdrawn so that there shall be no interference between the tines and said carriers, the movement downwardly of these tines as permitted by the receding or sloping part of the cam 84 continues until the arm 83 enters the notch 105. At that time the tines not held upwardly by the filling which should be present fall into a slot on the raceway, as above described. The constantly actuated rod 87 then is prevented from making a complete return movement as follower 98 is permitted to be lowered by cam 97, that causing the contact finger 109 to be halted or arrested temporarily in an intermediate position as indicated in Figs. 5 and 6. The actual filling feeding movement takes place just as the lay advances forwardly to effect beating-up of the filling and therefore finger 109 eventually contacts the switch actuator or plunger 110 thereby to trip the microswitch 111 and to complete a circuit through ground to the secondary 115 of the transformer and including closed switch 117 to energize the solenoid 54 for the detent 46. Then the said detent drops or moves to an active position for engagement by the contact member 44 and stopping is again effected as above described. It is to be understood that, contra to what may take place upon failure of warp thread, a filling failure indication

is always timed to the movement of the loom parts so that the drawing downwardly of the detent 46 by the solenoid at 54 occurs just prior to approach of cam 38 or in about the position at which the parts are shown in Fig. 2, therefore there is no possibility of the filling stop indication being completed to stop the loom by anything other than cam 38 which is expressly designed and adjusted for that purpose. The knock-off of the loom parts includes throwing out the switch 117 so that in either a warp stop or filling stop, the entire stop motion circuit becomes dead and remains so until the loom is again started and switch 117 closed as the shipper lever 65 or that at the other end of the shaft 62 is pulled outwardly or otherwise moved to what is its active or loom running position.

To start the loom again after repairing the fault for which it was stopped, it is only necessary to pull the lever 65 or similar control lever to operative position; that then engages the clutch through the positive linkage, disengages the brake, if one is used, and closes switch 117.

This description has made mention of shuttleless looms wherein the picks of filling are inserted from each side. In certain instances filling may be inserted from one side only. The stop mechanism functions in the same general manner in either case.

The moving actuator has been shown as of the pivoted or swinging type. It may conveniently be provided for movement of other nature, e. g., one in which the actuator slides in a rectilinear or other pathway. It may be positively controlled in each direction of its movement, or may be spring returned.

While one embodiment of the invention has been disclosed, it is to be understood that the invention concept may be carried out in a number of ways. The invention is, therefore, not to be limited to the precise details described, but is intended to cover all variations and modifications thereof falling within the spirit of the invention and the scope of the claims.

We claim:

1. In a stop motion for a loom, a periodically moving actuator, a means to disconnect a source of power from the loom, a detent pivotally mounted upon said means to disconnect the source of power from the loom and movable transversely to the directions of movement of said power disconnecting means to and from a position between the moving actuator and the means for disconnecting the source of power so that movements of the actuator are conveyed through to the means for disconnecting the source of power when said detent occupies a position between the said parts, and thread sensing means effective upon sensing an abnormality in the condition of the thread, to move said detent into said position between the moving actuator and means to disconnect power from the loom.

2. In a stop motion for a loom, a periodically moving actuator, a means to disconnect a source of power from the loom, detents movable to and from a position between the moving actuator and the means for disconnecting the source of power from the loom, means for sensing the condition of warp threads and other means for sensing the presence or absence of filling properly inserted in the shed, means for normally holding said detents out of a position in which they would be engaged by said moving actuator said sensing means being operable upon indicating an abnormality in either the warp threads or in the filling for moving the

detent affected thereby to a position in the path of said moving actuator thereby to stop the loom upon a succeeding stroke of the moving actuator.

5. In a stop motion for a loom, a periodically moving actuator, a means to disconnect a source of power from the loom, detents movable to and from a position between the moving actuator and the means for disconnecting the source of power from the loom, a circuit comprising a source of current, solenoids, one for one of said detents and another for the other of said detents and warp thread sensing and filling thread sensing means each of which is effective upon a solenoid within the circuit for varying its respective solenoid to move the respective detent controlled thereby into the path of the moving actuator.

4. In a stop motion for a loom, a periodically moving actuator comprising a pivoted arm, a contact surface and a follower at the free end of said arm, a cam means engageable with said follower, a means to disconnect a source of power from the loom comprising a movable member aligned with said contact surface but out of range of the movement thereof, a detent movable to and from a position between the contact surface of the moving actuator and the means to disconnect the source of power from the loom, and thread sensing means effective upon sensing an abnormality in the condition of the thread, to move said detent into a position between said moving actuator and the means to disconnect power from the loom, whereby on the next following movement of the actuator by said cam means, the power for the loom will be disconnected therefrom.

5. In a stop motion for a loom, a periodically moving actuator comprising a pivoted arm, a contact surface and a follower at the free end of said arm and a cam means constantly rotatable and engageable with said follower for moving the actuator throughout a limited angular extent, a means to disconnect the source of power from the loom comprising a movable member aligned with said contact surface but disposed out of range of movement thereof, a detent supported adjacent said means for disconnecting the source of power and movable to and from a position between the contact surfaces of the moving actuator and the means to disconnect the source of power from the loom, said detent having a thickness such that when moved to a position between the moving actuator and means for disconnecting the source of power, further movements of the said actuator affect the said means to cause it to disconnect the source of power from the loom, and thread sensing means effective upon sensing an abnormality in the condition of the thread, to move said detent into a position between said moving actuator and the means to disconnect the source of power from the loom.

6. In a stop motion for a loom, a periodically moving actuator comprising a pivoted arm, a contact surface and a follower at the free end of said arm and a cam means constantly rotatable and engageable with said follower for moving the actuator throughout a limited angular extent, a means to disconnect a source of power from the loom comprising a movable member a part of which is aligned with said contact surface but disposed out of range of movement thereof, detents supported adjacent said means for disconnecting the source of power and movable to and from a position between the contact surfaces of the moving actuator and the means to disconnect the source of power from the loom and having a

thickness such that when moved to a position between the moving actuator and means for disconnecting the source of power, further movements of the said actuator affect the said means to cause it to disconnect the source of power from the loom, and thread sensing means including warp thread sensing and filling thread sensing devices each of which is effective upon sensing an abnormality in its respective thread for moving one of the said detents into a position between the moving actuator and the means to disconnect the source of power from the loom, whereby on the next following movement of the actuator by said cam means, the loom will be knocked off and stopped.

7. In a stop motion for a loom, a constantly rotating shaft, a periodically moving actuator comprising a pivoted arm, a cam means fixed to said shaft and a follower at the free end of said arm and engageable by said cam means, a clutch engaging and releasing means on said shaft, a knock-off lever including an arm and fork engageable with said releasing means, said moving actuator being movable by said cam means to an extent insufficient to affect the said arm and fork, and a detent positionable between said fork and moving actuator and of such thickness as to impart movement of the actuator to the fork and clutch engaging and releasing means to knock off and stop the loom.

8. In a stop motion for a loom, a periodically moving actuator comprising a pivoted arm, a contact surface and a follower at the free end of said arm and a cam means engageable with said follower, a means to disconnect a source of power from the loom comprising a movable member aligned with said contact surface but out of range of movement thereof, a plurality of detents pivoted for movement upon said means for disconnecting the source of power and movable to and from a position between the contact surface of the moving actuator and a part of the means to disconnect the source of power from the loom opposite to said contact surface and of such thickness that when moved to such position between the contact surface of the moving actuator and the said part of said means, further movements of the actuator under the influence of said cam means causes a corresponding movement of the means for disconnecting the source of power, a circuit comprising a source of current, solenoids, one for each of said detents, warp thread sensing means in said circuit and interconnected therein for energizing one said solenoid, filling thread sensing means likewise forming a part of said circuit and so disposed therein that upon failure of filling thread to be inserted properly within the fabric, that the solenoid in that part of the circuit controlled by said filling thread sensing means shall be energized, said solenoids being so disposed and so connected with respect to said detents that upon energization thereof, the said detents are moved into alignment with the contact surface of the moving actuator.

9. In a stop motion for a loom, a constantly rotating shaft, a periodically moving actuator comprising a pivoted arm, a cam means fixed to said shaft and a follower at the free end of said arm and engageable by said cam means, said cam means comprising a disc-like member, cams fixed thereto and angularly spaced, one of which functions to impart movements incidental to stopping upon failure of the warp thread and the other of which governs stopping movements re-

sulting upon failure of filling to be inserted properly, a clutch engaging and releasing means on said shaft, a knock-off lever including an arm and fork engageable with said releasing means, 5 said moving actuator being movable by said cams to an extent insufficient to contact and affect the said arm and fork, detents pivoted to said knock-off arm and fork means and having portions thereof which are engageable by said moving actuator when the said detents are moved to a position in alignment with the said actuator, said detents being of a thickness such that when interposed between the actuator and the fork, movements of the actuator are conveyed through 10 the detent to the fork and thereby to the engaging and releasing means and interconnections therefrom to the said detents for moving them from a normally inactive position to one in which they are interposed between the moving actuator 15 and the fork whenever an abnormality in the condition of the thread is indicated.

10. In a stop motion for a loom, a constantly rotating shaft, a periodically moving actuator comprising a pivoted arm, a cam means fixed to said shaft and a follower at the free end of said arm engageable by said cam means, an adjustable contact member at the said free end of the arm adjacent the follower, said cam means comprising a disc, cams attached to the side of said 20 disc adjacent the follower and aligned therewith, said cams being angularly spaced, a clutch engaging and releasing means slidable along said shaft, a knock-off lever including an arm and a fork engageable with said slidable releasing means, said moving actuator being movable by said cam means to an extent insufficient to affect the said arm and fork, an extension to said fork and detents pivoted at either end of said extension and having contact portions at their ends 25 which terminate adjacent the central portion of said extension and in alignment with the said contact member of said moving actuator when moved to an active position, said detents being of such thickness that when moved to active 30 position and contacted by said moving actuator, the extension and fork will be moved to disengage the clutch and to knock off the loom, resilient means normally maintaining said detents in a position out of range of said moving actuator, stop motion devices associated with the warp threads and with the filling threads and means interconnecting said stop motion devices to said detents for moving them against the said resilient means to a position to be engaged by 35 the moving actuator upon an indication of failure at any one of the warp threads or failure of a filling thread to be properly inserted.

11. Mechanism as defined in claim 10, wherein 40 one of the said cams attached to the cam disc is employed for moving the actuator to complete stopping of the loom whenever a warp thread failure is indicated and the other said cam is employed for similarly stopping the loom upon failure of filling thread properly to be inserted, 45 and a cam adjacent the said cam which effects stopping upon failure of filling, an extension on that detent controlled through the warp thread stop indicating means, said extension being engageable with said cam to maintain the detent out of range of the moving actuator during passage of the said cam which controls stopping upon failure of filling thereby to prevent stopping of the loom when a warp thread failure is indicated, except by the cam specifically intended.

12. In a stop motion for a loom having a rock shaft and a lay including a lay beam and swords pivoted at said rock shaft, a center fork comprising filling thread feeling tines, cam means effective to swing said tines through filling feeling and indicating movements, a shaft movable lengthwise of said lay beam to which said cam means are fixed and by which they are moved, and means for periodically reciprocating said shaft comprising a cam rotatably mounted on said rock shaft, means for rotating said cam, a bar guided for movement substantially lengthwise of one of said swords adjacent said cam on the rock shaft, a follower on said bar and in contact with said cam, and means interposed between said shaft and bar and supported upon the lay sword for imparting movements of the bar to the shaft.

13. In a stop motion for a loom having a rock shaft and a lay including a lay beam and swords pivoted at said rock shaft, a center fork comprising filling thread feeling tines, cam means effective to swing said tines through filling feeling and indicating movements, a shaft movable lengthwise of said lay beam to which said cam means are fixed and by which they are moved, and means for periodically reciprocating said shaft comprising a cam rotatably mounted on said rock shaft, means for rotating said cam, a bar and means for guiding said bar in substantial lengthwise alignment with one of said swords, fork means at one end of said bar engageable with means adjacent said cam on the rock shaft for maintaining alignment of that end of the bar with the shaft but permitting reciprocation of the bar, a follower carried by said bar and fork means and engageable with the cam whereby reciprocatory movements are imparted by the cam to the bar, a swinging lever means carried by said sword and connected to the shaft and engageable by the bar for imparting movements thereof to the shaft.

14. In a stop motion for a loom having a rock shaft and a lay including a lay beam and swords pivoted at said rock shaft, a center fork comprising filling thread feeling tines, cam means effective to swing said tines through filling feeling and indicating movements, a shaft movable lengthwise of said lay beam to which said cam means are fixed and by which they are moved, and means for periodically reciprocating said shaft comprising a cam rotatably mounted on said rock shaft, means for rotating said cam, a bar and means for guiding said bar in substantial lengthwise alignment with one of said swords, fork means at one end of said bar engageable with means adjacent said cam on the rock shaft for maintaining alignment of that end of the bar with the shaft but permitting reciprocation of the bar, a follower carried by said bar and fork means and engageable with the cam whereby reciprocatory movements are imparted by the cam

5 to the bar, and means for imparting movements from the bar to the shaft which comprises a lever arm connected to the shaft, a second lever arm movable with the first and engageable by that end of the bar adjacent thereto, spring means for returning the shaft in one direction, the connection to the lever and bar being such that movement is imparted to the lever by the bar in one direction only.

10 15. In a stop motion for a loom having a rock shaft and a lay including a lay beam and swords pivoted at said rock shaft, a center fork comprising filling thread feeling tines, cam means effective to swing said tines through filling feeling and indicating movements, a shaft movable lengthwise of said lay beam to which said cam means are fixed and by which they are moved, and means for periodically reciprocating said shaft comprising a cam rotatably mounted on said rock shaft, means for rotating said cam, a bar guided for movement substantially lengthwise of one of said swords adjacent said cam on the rock shaft, a follower on said bar and in contact with said cam, and means interposed between said shaft and bar and supported upon the lay sword for imparting movements of the bar to the shaft, a switch means through which a circuit controlled for stopping the loom, and a contact finger carried by said means for imparting movements of the bar to the shaft for affecting said switch means when the means for imparting movements of the bar to the shaft and the shaft are stopped in an intermediate position.
